DESIGN FOR A CONTAINER FOR CANDY, PERFUME, FLOWERS, AND THE LIKE

King Harrington, San Francisco, Calif.

Application December 5, 1945, Serial No. 124,371

Term of patent 14 years

(Cl. D58—11)

To all whom it may concern:

Be it known that I, King Harrington, a citizen of the United States, and a resident of the city and county of San Francisco, State of California, have invented a new, original, and ornamental Design for a Container for Candy, Perfume, Flowers and the like, of which the following is a specification, reference being had to the accompanying drawing, forming part thereof:

Figure 1 is a top plan view of a container for candy, perfume, flowers and the like showing my new design.

Figures 2 and 4 are each side elevations of the opposite sides of the container for candy, perfume, flowers and the like; while

Figures 3 and 5 are each end views of the opposite ends of the container for candy, perfume, flowers and the like.

I claim:

The ornamental design for a container for candy, perfume, flowers and the like, as shown.

KING HARRINGTON.
